DESCRIPTION

FIG. 1 is a front elevation view of an album for holding photographs, negatives and a digital disc, showing my new design, the album being shown with its covers in a closed condition;

FIG. 2 is a left side view thereof;

FIG. 3 is a top view thereof, the bottom view being a mirror image;

FIG. 4 is a right side view thereof;

FIG. 5 is a rear elevation view thereof;

FIG. 6 is an interior elevation view of the album with its covers in an open condition, shown with the leaves thereof for holding photographs positioned away from one cover; and,

FIG. 7 is an interior elevation view of the album with its covers in an open condition, shown with the leaves thereof positioned away from the other cover.

The cross hatch shading employed in FIGS. 6 and 7 is understood to represent fabric. The uniformly spaced dashed lines in FIGS. 6 and 7 are understood to represent welds.
